UNITED STATES PATENT OFFICE.

OSCAR MUSSINAN, JR., OF NEW YORK, ASSIGNOR TO EBERHARD FABER,
OF PORT RICHMOND, N. Y.

PENCIL.

SPECIFICATION forming part of Letters Patent No. 317,838, dated May 12, 1885.

Application filed November 13, 1884. (No model.)

To all whom it may concern:

Be it known that I, OSCAR MUSSINAN, Jr., a citizen of the United States, residing at New York, in the county and State of New York, have invented new and useful Improvements 5 in Pencils, of which the following is a specification.

My invention relates to improvements in lead-pencils; and it consists in the combination, with a case or handle and a lead-receiver, of a split lead-clamp secured to the lead-receiver and provided with a cone, a conical sleeve, which slides on said split clamp and is arranged to operate upon the cone, and a 15 disk or stop secured to the case.

On the accompanying drawings, Figure 1 is a longitudinal section of my pencil, showing the position of parts to effect the clamping of the lead. Fig. 2 is a longitudinal section of 20 the same showing the pencil ready for use. Fig. 3 is a longitudinal section showing the lead unclamped. Fig. 4 shows a modification of part of the pencil.

Similar letters indicate corresponding parts. 25 In the drawings the letter A designates the tubular case or handle, which is made of any convenient length or size. On its lower end the case A tapers, forming part of a cone, a, said cone being provided with an inner bead, a'.

Onto the upper end of the case A is snugly 30 fitted a lead-receiver, B, which has drilled into it a longitudinal hole for the reception of the extension of the split lead-clamp C and the lead E contained therein. The lead-clamp C is securely glued to the lead-receiver B; or it may be fastened in any other suitable manner.

Near the lower end of the lead-clamp C is 40 formed a cone, d, the slot g in said lead-clamp extending also through the cone d.

c is a conical sleeve, which slides on the lead-clamp C, and is of such a size that when it is forced upon the cone d the split clamp 45 C is sufficiently tightened upon the lead E contained therein to hold said lead E firmly in position.

F is a disk or stop fitted in the case A, and is secured therein in position by a screw, f, or, 50 by preference, it may be secured, as shown in Fig. 4, by means of two inner beads, f' f', formed in the tubular case A, the latter method of fastening being stronger, and also

serving to improve the appearance of the pencil.

The lead-receiver B, before mentioned, is fitted in the case A so that it requires some little force to push the same backward and forward in the case A, in order to prevent slipping of the lead-receiver when the pencil is in 55 use. If, now, the lead-receiver B, from the position shown in Fig. 3, be drawn backward in the case A the cone d is brought into contact with the sleeve c, and causes said sleeve c to be carried along until it is brought to a stop by the disk F. On further drawing backward the lead-receiver B, the cone d is forced into the sleeve c, and the lead-clamp C is forced upon the lead, Fig. 1. If the lead-receiver B is now pushed forward until the 60 pencil projects beyond the lower part of the case A, or until the sleeve c strikes lightly against the bead a' on the inner surface of the conical part a of the case, as shown in Fig. 2, the pencil is ready for use.

In order to return the lead from the lead-clamp C and allow the same to slide in the lead-receiver B, the lead receiver is pressed forward to such a position that the sleeve c impinges against the bead a' on the conical 65 part a of the case A, and is forced back from the cone d, which allows the lead-clamp C to expand, Fig. 3.

As will be seen from the above description and the drawings, the construction and mechanism of my improved pencil are extremely 70 simple, but at the same time very efficient and durable, and it allows of adjusting the lead very easily and quickly.

What I claim as new, and desire to secure 75 by Letters Patent, is—

The combination, substantially as hereinbefore described, with the case or handle A and the lead-receiver B, of the split lead-clamp C, secured to the lead-receiver and provided 80 with the cone d, the conical sleeve c, sliding on the split lead-clamp C and arranged to operate upon the cone d, and the disk or stop F, secured to the case A.

In testimony whereof I have hereunto set 85 my hand and seal in the presence of two subscribing witnesses.

OSCAR MUSSINAN, JR. [L. S.]
